CHARLES M. WEMPNER, OF ST. LOUIS, MISSOURI, ASSIGNOR TO ST. LOUIS BRASS MANUFACTURING COMPANY, OF ST. LOUIS, MISSOURI, A CORPORATION OF MISSOURI.

LIGHTING FIXTURE.

1,413,439.

Specification of Letters Patent. Patented Apr. 18, 1922.

Application filed November 26, 1919. Serial No. 340,717.

To all whom it may concern:

Be it known that I, CHARLES M. WEMPNER, a citizen of the United States of America, residing at the city of St. Louis, State of Missouri, United States of America, have invented a certain new and useful Lighting Fixture, of which the following is such a full, clear, and exact description as will enable any one skilled in the art to which it 5 appertains to make and use the same, reference being had to the accompanying drawings, forming part of this specification.

My invention relates to a lighting fixture adapted for the illumination of counters and 10 desks in banking rooms and the like and is particularly directed to the means for controlling the light emitted in a manner consistent with efficient utilization of the light produced by the source. Another object is 15 to produce a fixture all parts of which are accessible for cleaning without disassembly.

In the drawings, Figure 1 is a vertical cross section illustrating one embodiment of 20 my invention; Figure 2 illustrates a modification; and Figure 3 is a view partly in cross section and partly in elevation along the line 3—3 of Figure 1. 1 represents a compartment or container preferably of sheet metal which may be attached to a wall or 25 counter frame work by means of screws or in any other suitable manner. The lamps 3 are supported from the wall of the wire conduit 4 by means of the stem 5. 6 and 7 are light shields of translucent material preferably 30 opal glass and the surface exposed to the light is adapted to reflect a portion of the light.

As shown in Figure 1, the shields 6 and 7 are pivoted at points substantially in horizontal alignment with the lamps and the surfaces of the shields above the pivots are at an angle to the surfaces below the pivots. In this figure the top and bottom of the container are both open. By adjusting the 45 lower portions of the shields 6 and 7 toward and away from each other the proportion of direct rays emitted downward to the rays transmitted downward through the shields and diffused thereby can be varied at will. In this figure the top and bottom of the container are both open. By adjusting the lower portions of the shields 6 and 7 toward and away from each other the proportion of direct rays emitted downward to the rays transmitted downward through the shields and diffused thereby can be varied at will. 50 and the intensity and character of the light on the counter thereby adjusted to suit the convenience of the user. When the lower halves of the shields are moved to their open positions the upper halves are brought 55 inward to positions in which they reflect

some of the light downward and thus further increase the illumination on the desk. When the lower halves are brought to closed position their surfaces reflect upward some of the light emitted downwardly from the 60 lamp and increase the upward illumination produced by the fixture.

A common practice in fixtures of the general type herein described is to provide a lower plate of translucent glass closing the 65 bottom of the fixture. This is subject to the objection of having no means of regulation and to the further disadvantage that the glass must be removed, with the consequent dangers of breakage, in order to clean it and 70 the interior of the fixture. In my improved fixture, it will be noted that the translucent reflecting glass is all accessible for cleaning without any disassembly or removal of any part and that the fixture is capable of producing the lighting effect on the desk which 75 would result from either clear or translucent glass in the bottom of the fixture.

In the modification illustrated in Figure 3 the upper half of the shields of Figure 1 80 have been omitted and the shape of the shields somewhat modified but the general principle of operation so far as downwardly controlled light is concerned is the same. In this type of fixture the top of the compartment can be closed as indicated and the under surface polished or means otherwise provided for forming a reflector.

Having fully described my invention, what I claim as new and desire to secure by Letters Patent of the United States is:

1. A lighting fixture comprising a horizontally disposed container, a source of light in the container and shields of translucent material on opposite sides of the perpendicular axis of the light source and extending below the horizontal axis of said source, said shields being adjustable toward and away from each other at their lower ends to control the proportion of direct to diffused rays 95 emitted downward from the fixture.

2. A lighting fixture comprising a horizontally disposed container open at the bottom and having an opaque front wall, a source of light in the container and shields 105 of translucent material on opposite sides of the perpendicular axis of the light source and extending below the horizontal axis of said source, said shields being adjustable toward and away from each other at their 110

lower ends to control the proportion of direct to diffused rays emitted downward from the fixture.

3. A lighting fixture comprising a horizontally disposed container, a source of light in the container, shields of translucent material on opposite sides of the perpendicular axis of the light source and extending above and below the horizontal axis of said source and means for adjusting the angular position of the shields to control the proportion of direct to diffused rays emitted downward from the fixture.

4. A lighting fixture comprising a horizontally disposed container, a source of light in the container, shields of translucent material on opposite sides of the perpendicular axis of the light source and extending above and below the horizontal axis of said source, said shields having surfaces adapted to reflect a portion of the light, and means for adjusting the angular position of the shields to control the proportion of diffused rays to direct and reflected rays emitted downward from the fixture.

5. A lighting fixture comprising a horizontally disposed container, a source of light in the container, shield members of translucent material on opposite sides of the perpendicular axis of the light source and extending above and below the horizontal axis of said source, and supporting and adjust-

ing means for the shields whereby the upper shield members are brought toward each other when the lower shields are separated. 35

6. A lighting fixture comprising a horizontally disposed container, a source of light in the container, a light shield on one side of the perpendicular axis of the light source and extending above and below the horizontal axis of said source, the upper part of said shield being in a different plane from the lower part, and supporting and adjusting means for the shield whereby when the lower end is moved in one direction the upper end 45 will move in the opposite direction.

7. A lighting fixture comprising a horizontally disposed container, a source of light in the container, a light shield on each side of the perpendicular axis of the light source 50 and extending above and below the horizontal axis of said source, the upper part of each shield being in a different plane from the lower part, and supporting and adjusting means for the shields whereby when the 55 lower end of a shield is moved in one direction the upper end will move in the opposite direction, the upper part of each shield being adapted to reflect light downward when the lower part is in full open position. 60

In testimony whereof, I have hereunto set my hand and affixed my seal.

CHARLES M. WEMPNER. [L. s.]
